DISPLAY PACKAGING CONTAINER

John Donald Bostrom, Niles, Ill., assignor to Poster Packaging, Inc., Chicago, Ill., a corporation of Delaware

Filed Mar. 8, 1961, Ser. No. 64,186

Term of patent 14 years

(Cl. D58—12.6)

FIG. 4

FIG. 2

FIG. 3

The lid for the container shown in broken lines is plain.

The essential features of the design are shown in full lines.

I. claim:

The ornamental design for a display packaging container, as shown and described.
